MISSOURI.

ENGINE FUEL-PUMP.

1,341,640.

Specification of Letters Patent. Patented June 1, 1920.

Application filed August 29, 1917, Serial No. 188,733. Renewed April 1, 1920. Serial No. 370,533.

To all whom it may concern:

Be it known that I, ARTHUR S. HAWKS, a citizen of the United States of America, residing in St. Louis, Missouri, have invented 5 the following-described Improvements in Engine Fuel-Pumps.

The invention concerns an organization of fuel pumping and control elements for the supply of liquid fuel under high pressure to injection type engines, such as Diesel engines, and more especially relates to the means herein described and broadly claimed whereby the fuel delivery is subject to sensitive control to suit the load or the desired 10 speed, and of auxiliary and independent controls for starting and emergency needs and whereby the delivery of a plurality of individual pumping cylinders to their respective engine cylinders is subject to coincident sensitive and equal control in conjunction with other controls, by groups, and altogether for emergency. The invention further relates to the relative arrangement of the cylinders and pump and control valves or 15 members, whereby the structure occupies but small space and all of the various controls therein are coördinated in compact and rugged form, all as hereinafter made fully apparent to those skilled in the art.

30 In the accompanying drawings, which illustrate the preferred embodiment of the invention,—

Figure 1 is a side elevation illustrating the principal parts and also certain portions 35 of the engine to which the fuel pump is applied;

Fig. 2 is a top plan of the parts shown in Fig. 1;

Fig. 3 is a horizontal section through the 40 plane of the pumping cylinders on line III—III with certain parts in plan;

Fig. 4 is a vertical section on line IV—IV of Fig. 3, in the direction of the arrows;

Fig. 5 is a cross section on line V—V of 45 Fig. 2 with the pump body in elevation; and

Fig. 6 is an elevation taken from the left hand side of Fig. 5.

Pumping apparatus according to the present invention may be applied to injection 50 type engines of various designs and sizes and is illustrated in the figures just referred to as applied to a multi-cylinder engine and so arranged thereon as to be driven by an eccentric or crank mechanism.

concealed within the shaft housing marked 55 1 in Fig. 1. The pump body is bolted by its flange 2, at one end, to this housing and supported at its other end by a bracket 3 which may be secured to the engine structure in any suitable way. The several pumping 60 cylinders, of which there are six in the present case and marked 4, are bored in the pump body in double opposed rows and all in the same plane, which is a horizontal plane for the case in hand, so that there are 65 thus three pumping cylinders on each side of the pump body. The pumping plungers, marked 5, of each group of three cylinders are all connected to a common cross-head 6 and both cross-heads are joined by yoke 70 rods 7 sliding in bearings 8 on opposite sides of the pump body as illustrated in Fig. 3. The yoke structure thus formed is connected to the eccentric strap partially shown in Fig. 3 and there marked 9, so that the 75 entire group of plungers moves in unison and each stroke imparted by the eccentric is a pumping stroke for the group of cylinders on one side of the pump or the other. The inner ends of the horizontal pumping 80 cylinders open into their respective valve chambers which are formed in the central upstanding part 10 of the pump body and the suction valves 11 for each of the several cylinders are disposed at the upper ends of 85 such chambers, being arranged in rows transverse to the plane of the cylinders and also to the axes thereof.

The said suction valves serve to admit the fuel to the cylinders through suitable ports 90 not necessary to be referred to and they also serve the further purpose of regulating the fuel delivery from their respective outlet valves 12, being for this purpose mechanically actuated by the pair of bell-crank 95 valve levers 13 and also controlled thereby, as to their time of closing and in accordance with the principles of charge regulation which is fully disclosed in the Lauster Patent No. 729,613. For the case in hand 100 the said suction valves may be regarded as representing fuel charge regulating valves or members of any suitable character or mode of operation, the stroke period of which is variably coördinated with the yoke 105 structure or the main pumping elements of the apparatus. The bell-crank levers 13 are reverse duplicates of each other and each

has a power arm 13^a extending downward toward the reciprocating yoke structure at one side of the pump body and a working arm 13^b above said body and above the upper standing portion 10 thereof and extending toward the proximate row of regulating valves 11 therein. Each bell-crank lever is fulcrumed on a pair of eccentric bearings 14 formed on one of a pair of parallel rock shafts 15 which latter are journaled in brackets 16 formed on or bolted to the opposite sides of the pump body. The two eccentric bearings 14 on each rock shaft are disposed near the supported ends thereof (Fig. 5) and the hub portion of the bell-crank lever is divided into two parts respectively mounted on each eccentric bearing and joined by the cross bar 13^c which is parallel to the row of valves 11 and carries the adjustable thrust screws 20 for engaging the stems of each of them. Each power arm 13^a extends into the path of one of a pair of tappets 17 formed on a sleeve secured fast to the yoke rod 7 on one side of the pump body and is so related thereto that the bell-crank will be operated to operate its corresponding row of regulating valves in some predetermined relation to the pumping stroke of the cylinders to which said row of valves pertains. In the case in hand and wherein the regulating valve is the suction valve of the pump, the bell-crank valve lever for such valve or row of valves is struck by the tappet on the suction stroke for the cylinders on that side of the pump and the suction valves are thereby opened (if they have not already been opened by the inflowing fuel). On the beginning of the ensuing force stroke the valve is initially held open by the bell-crank and will not be permitted to close until the tappet arm 17 parts contact with arm 13^a or at least permits its return to some determinate position and until such point is reached the suction valve remaining open, allows a part of the fuel sucked in on the previous stroke to be returned back through it. Only that part which remains after the valve has closed upon its seat will be forced through the delivery valve and delivery tube 18 to the injection valve on the engine cylinder. The charge admitted to the engine is thus dependent on the manner or period of engagement, or disengagement, of the tappet with its bell-crank and can be varied by varying that period. For this purpose and according to the present invention several controls and several adjustments are provided, all adapted to change the relation of the bell-crank either to its tappet arm or to the regulating members or both. The striker screws 19 in the end of each tappet arm 17 constitute one of such adjustments, the principal use of which however, may be merely as a take-up for wear. The thrust

screws 20 carried on the cross bar 13^c of each bell-crank, serve to adjust the relation of each valve or regulating member, individually, to that crank and for obvious purposes. The running control of the bell-crank is accomplished by rotating the rock shafts 15 on which said cranks are eccentrically fulcrumed and such rotation is done by a crank arm 21 secured to the end of one of said shafts and connected to the other shaft by the segment gears 22 which closely and accurately intermesh so that both shafts receive equal angular displacement from the crank arm 21 and correspondingly and equally vary the position of the fulcrum axes of the bell-crank and hence of the relative timing of the fuel regulating members 11.

It will be observed that it is by virtue of this or equivalent inter-gearing of the valve lever shafts which imparts an equal control motion to each, that the multiple pumping cylinders can be conveniently and practically disposed in the double opposed rows above described and with the suction valves or other regulating members disposed centrally of the pump body and compactly related to the operating members or pumping element on opposite sides thereof. It will be further observed that by reason of the location of the fulcrum axes of the bell-crank lever in the relative position above described and with power arms extending toward the plane of the reciprocating yoke structure, a reliable and proper coordination of said levers and through them of the fuel regulating means is attained. Fuel pumps with pumping elements thus divided and organized can be made in extremely compact form for very large sizes of multi-cylinder engines and with remarkable accuracy of regulation with respect to the delivery to each engine cylinder. The operating connections 23 (Fig. 1) run from the crank arm 21 to the operator's control stand and will be understood to be the agency whereby the operator adjusts the speed of the engine although in some types of engines the said connections might run to an engine governor of the usual type.

The bell-crank levers 13 are urged by spring pressure toward their inactive positions and in the case shown a single spring 24 joining the two arms 13^a serves this purpose. Either or both bell-cranks may be swung on its bearings against the pull of this spring and independently of the adjustments above described and also independently of the running control imparted to the inter-gearred rock shafts 15, and may be swung or rocked thereon to such extent as to depress the regulating members 11 and hold them depressed irrespective of the reciprocation of the pumping plungers and so as to render either group or both groups 13^b

of pumping cylinders completely inoperative to deliver fuel. For emergency conditions both bell-crank levers are so depressed, and simultaneously, by means of 5 the control lever 25, fulcrumed on one of the rock shafts 15 and connected by one arm to an emergency governor indicated at 26 (Fig. 1). The other arm of this lever overlies the cross bars 13^a of both bell-cranks 10 and by its thrust screws 27 is adapted to engage and depress said bars, spreading the power arms 13^a wide apart and away from their respective tappets as will be obvious. When this emergency lever acts the entire 15 pump mechanism is instantly cut out of action to deliver fuel to the engine, since the suction valves 11 remain open throughout both directions of reciprocation of the reciprocating yoke structure.

20 Independent control of the each bell-crank is accomplished by the two levers 28 loosely mounted one on each of the rock shafts 15 between the supporting bearings thereof and the hubs of the segment gears 22. The 25 inner arms of these levers overlie and engage the studs 29 which project from the ends of the cross bars 13^a and their outer arms are connected to rods 30 so that a pull on either rod will swing one or the other bell-crank and thereby depress the regulating valves of the corresponding cross bar and cut out of action either group of pumping cylinders independently of the other. On such movement the bell-crank merely 35 turns on its eccentric bearing 14, its power arm 13^a swinging away from its tappet arm 17 and independently of the angular position of the rock shaft on which it is carried. The two pull rods 30 run to the starting 40 gear of the engine, not shown, being there mechanically coördinated with other parts whereby the engine cylinders, which are used for starting by means of air pressure are automatically shut off from the source 45 of fuel supply while being so used or at any other time when the delivery of fuel is not needed, as when reversing the direction of the engine.

From the foregoing description it will be 50 apparent that the advantages of individual and group control, and of joint regulation of fuel delivery can be readily obtained by other forms of mechanical structure and it is to be understood that except as specified 55 in the appended claims there is no intentional limitation to the structure of the drawings.

Claims:

1. In an injection type combustion engine, a fuel pump comprising in combination with the pumping cylinder and piston and mechanism for operating the latter, a 60 mechanically operated, delivery regulating member, an operator's control to vary the timing of said member and an emergency

means for rendering said member inoperative.

2. In an injection type combustion engine, a fuel pump comprising in combination with the pumping elements, a pump-operated, delivery-regulating, valve, an operator's control to vary the timing of said valve, an emergency governor control therefore for adapted to render said valve inoperative and a second operator's control also adapted to render the same inoperative. 70

3. In an injection type combustion engine, a fuel pump comprising in combination with the pumping elements thereof, a delivery-regulating member, a pump-operated, eccentrically fulcrumed lever for actuating the same, a control means for shifting the axis of said fulcrum and a control means for swinging said lever on its fulcrum independently of the pumping elements. 80

4. In a multi-cylinder injection-type combustion engine, fuel pump apparatus having multiple pumping cylinders divided into groups, means for conjointly varying the delivery from both groups according to the load and independent means for rendering either group inoperative for effecting delivery of fuel. 90

5. In a multi-cylinder injection type combustion engine, fuel pump apparatus having multiple pumping cylinders divided into groups, means comprising two inter-geared rock shafts for conjointly varying the delivery from both groups and independent means for rendering either group inoperative for effecting delivery of fuel. 95

6. In a multi-cylinder engine, fuel pump apparatus having multiple pumping cylinders divided into groups and disposed in double opposed arrangement, means for conjointly varying the delivery from both groups and independent means for rendering either group inoperative. 100

7. In a multi-cylinder combustion engine in combination, a fuel pump having multiple pumping cylinders divided into groups, means for conjointly varying the fuel delivery from all of the cylinders in both groups, means for cutting out delivery from either group independently of the other group and an emergency means for simultaneously cutting out both groups. 110

8. In a multi-cylinder combustion engine, a fuel pump having multiple pumping cylinders divided into double opposed groups, 120 a pair of inter-geared rock shafts adapted for conjointly varying the fuel delivery from all of said cylinders, and means for cutting out delivery from either group independently of the other group. 125

9. In a multi-cylinder combustion engine, in combination, a multi-cylinder fuel pump, a pump-operated eccentrically fulcrumed lever for controlling the delivery from the cylinders thereof, a control for shifting the 130

axis of said lever to vary the said delivery and a second control for swinging said lever on its fulcrum independently of the position of the axis of said lever.

- 5 10. In a multi-cylinder fuel pump for injection-type engines, the combination with a mechanically operated, delivery-regulating member for each cylinder of a bar operated by the pumping elements and common to a 60 group of said members and adapted for controlling the same, means for independently adjusting the relation of each regulating member to said bar and a control means for varying the relation of said bar to the 65 pumping elements to regulate the fuel delivery from the whole group.
- 10 11. In a multi-cylinder fuel pump for injection-type engines, the combination with delivery regulating valves for each cylinder, 70 of a member operated by the pumping elements and common to a group of said valves and adapted for controlling the periods thereof, means for independently adjusting the relation of each valve to said member, a 75 control means for varying the relation of said member to the pump element and means independently of the pump element for shifting said member to cut out delivery from all of the cylinders.
- 15 12. In a multi-cylinder fuel pump for injection-type engines, a row of parallel pumping cylinders disposed side by side, an engine reciprocated cross head occupying substantially the same plane as the 80 cylinders and connected to the plungers thereof, delivery regulating valves for said cylinders disposed transversely to said plane, a yoke-driven lever for actuating said valves and means for varying the relation of said lever to said valve.
- 20 13. In a multi-cylinder fuel pump for injection-type engines, a double row of opposed pumping cylinders occupying a single plane, an engine-reciprocated yoke structure 85 operating the plungers of said cylinders, a double row of delivery-regulating valves pertinent to said cylinders and between the same, a yoke-operated lever for each row of valves and means for varying the actuation 90 of said valves thereby.
- 25 14. In a multi-cylinder fuel pump, the combination with a reciprocating structure coördinated in action with the pumping plungers, an eccentrically fulcrumed valve 95 lever actuated thereby, a control for shifting the fulcrum and a member for rocking 100

the lever on its fulcrum independently of said reciprocating structure.

15. In a multi-cylinder fuel pump, the combination with a reciprocating structure 60 coördinated in action with the pumping plungers, an eccentrically fulcrumed valve lever actuated thereby, a control for shifting the fulcrum, a series of delivery regulating valves operated by said lever and 65 means for independently adjusting said valves to said lever.

16. In a multi-cylinder fuel pump, the combination with pumping cylinders and plungers, delivery regulating valves disposed transversely thereto, a bell-crank lever having one arm extended toward the plane of the plungers and operated in co-ordination therewith and its other arm extended into operating relation to said regulating valves and means for varying the relation of said bell-crank to vary the fuel delivery.

17. In a multi-cylinder fuel pump, the combination with pumping cylinders and 80 plungers, delivery regulating valves disposed transversely thereto, a bell crank lever having one arm extended toward the plane of the plungers and operated in coördination therewith and its other arm extended 85 into operating relation to said regulating valves and a fulcrum for said lever which is shiftable to vary the fuel delivery.

18. In a multi-cylinder fuel pump, the combination with pump cylinders and oppositely acting pump plungers therein, of a series of delivery regulating valves disposed transversely to the cylinders, two bell-crank valve levers each operated in coördination with the pumping stroke in one direction 95 and means for coincidentally altering the relation of both levers to vary the fuel delivery.

19. In a multi-cylinder fuel pump, the combination with the pump cylinders and 100 oppositely acting pump plungers therein, of a series of delivery regulating valves disposed transversely to the cylinders, two valve levers each operated in coördination with the pumping stroke in one direction 105 and a shiftable eccentric fulcrum for each lever provided with means for coincidentally and equally shifting said fulcrum.

In testimony whereof I have signed this specification.

ARTHUR S. HAWKS.
